ATTORNEY

UNITED STATES PATENT OFFICE.

JOHN LOUIS GAEBEL, OF MADISONVILLE, KENTUCKY.

SOAP-DISPENSING DEVICE.

Application filed December 8, 1922. Serial No. 605,688.

To all whom it may concern:

Be it known that I, JOHN LOUIS GAEBEL, a citizen of the United States, residing at Madisonville, in the county of Hopkins and 5 State of Kentucky, have invented new and useful Improvements in Soap-Dispensing Devices, of which the following is a specification.

This invention relates to toilet apparatus 10 or accessories and has for its object the provision of a novel device for dispensing granulated soap, the soap being initially disposed within the device in cake form and being ground or granulated as used.

15 An important object is the provision of a device of this character which is provided with novel means for grinding the soap the means being operable by the person using the device.

20 An additional object is the provision of a dispensing mechanism of this character which will be simple and inexpensive in manufacture, economical in the use of soap, efficient and durable in service and a general 25 improvement in the art.

With the above and other objects and advantages in view the invention consists in the details of construction to be hereinafter more fully described and claimed and illustrated in the accompanying drawings, in which:

Figure 1 is a perspective view of one form of the device,

Figure 2 is a vertical cross section therethrough,

Figure 3 is a horizontal section,

Figure 4 is a longitudinal section through a modified form,

Figure 5 is a vertical section therethrough 40 and

Figure 6 is a cross section.

Referring more particularly to the drawings and especially Figures 1 to 3, I have shown my device as comprising a preferably rectangular casing 10 designed to be mounted upon the wall of a lavatory or the like by means of attaching ears 11. The lower end of this casing is formed of inverted frusto-pyramidal shape as indicated 45 at 12 and the upper end is provided with a hinged cover 13 carrying a latch 14 operating with a keeper 15 on the casing.

50 Journaled through the lower portion of the casing are spaced parallel shafts 16 carrying toothed or roughened grinding rollers 17 and also carrying intermeshing gears 18.

One shaft is prolonged and is provided exteriorly of the casing with a crank handle 19.

It is designed that soap in cake form, indicated at A, be disposed within the casing 60 upon the grinding rollers 17. I provide a spring 20 on the cover engaging the soap and forcing the same downwardly into engagement with the rollers so that when the crank handle 19 is rotated and the rollers 65 operated to grind and granulate the soap the cake will be fed downwardly to the rollers continually.

In the form of the device shown in Figures 4 to 6, the numeral 25 designates an outer 70 casing rectangular in shape and having a frusto-pyramidal bottom 26 having a discharge opening 29'. Secured against the inside of one wall of this casing is a rack bar 28 having teeth at both sides. The top of 75 this outer casing is closed by a hinged cover 29 and suitable latch means 30 cooperating with the keeper 31 for holding the cover closed.

Slidably mounted within this outer casing 80 is an inner casing 32 of similar shape but naturally of somewhat smaller dimensions, this inner casing having its top open and its bottom 33 of frusto-pyramidal shape and terminating in a discharge spout 34 which 85 extends through the opening 29'.

Journaled transversely within the inner casing are shafts 35 carrying grinding rollers 36 and also carrying gears 37 which mesh with the teeth on the opposite edges 90 of the rack bar 28.

It is intended that a cake of soap A be placed within the inner casing 32, and for feeding the cake to the rollers I provide a coil spring 38 carried by the cover and engaging the soap.

In the operation of this form it will be seen that the operator first wets his hands and then presses upwardly with the palm of his hand on the spout 34. This will result in moving the inner casing 32 upwardly whereupon the gears 37 meshing with the stationary rack bar 28 will be rotated, causing the rollers 36 to rotate in opposite directions and granulating the soap. The soap 100 will pass between the rollers and drop out through the spout 34 onto the operator's hands. When the pressure against the spout 34 is relieved the spring 38 operates to return the parts to initial position while 105 operating continually to feed the soap to the grinding rollers.

From the foregoing description and a study of the drawings it will be apparent that I have thus provided a simply constructed and consequently inexpensive device for dispensing soap in granulated form as it is needed, the device thus operating to keep the soap cake in proper condition and prevent waste. Owing to the simplicity of the construction and the fewness of the parts 10 it is apparent that there is nothing to get out of order and that the device should have a long life and satisfactorily perform all of its functions.

While I have shown and described the 15 preferred embodiment of the invention it is of course to be understood that I reserve the right to make such changes in the form, construction and arrangement of parts as will not depart from the spirit of the invention 20 or the scope of the subjoined claims.

Having thus described my invention I claim:

1. A dispensing device of the character described comprising a casing having a movable top and having its bottom formed with a discharge opening, an inner casing slideable within said main casing and having a discharge spout extending through said discharge opening, a pair of grinding rollers journaled in the inner casing, said inner casing being designed to hold a cake of soap placed upon said rollers, and an operative connection between said inner casing and the rollers whereby to rotate the latter when said inner casing is slid upwardly.

2. A dispensing device of the character described comprising a casing having a movable top, the bottom of the casing being provided with a discharge opening, a pair of shafts journaled in the lower portion of the casing and carrying grinding rollers and gears, said casing being designed to contain a cake of soap, a spring carried by the cover for forcing the soap into engagement with the rollers and means for rotating the rollers, consisting of a rack meshing with the gears.

3. A soap dispensing device comprising an outer casing provided in its bottom with a discharge opening and provided at its top 50 with a removable cover, an inner casing slideable within the outer casing and having an outlet spout slideable through the discharge opening, a pair of grinding rollers journaled in the lower portion of the inner 55 casing and carrying gears, a stationary rack within the outer casing engaging said gears, said inner casing being designed to contain soap in cake form, and spring means for feeding the soap to the rollers.

4. A soap dispensing device comprising an outer casing provided in its bottom with a discharge opening and provided at its top with a removable cover, an inner casing slideable within the outer casing and having an 60 outlet spout slideable through the discharge opening, a pair of grinding rollers journaled in the lower portion of the inner casing and carrying gears, a stationary rack within the outer casing engaging said gears, said inner 65 casing being designed to contain soap in cake form, and spring means for feeding the soap to the rollers, consisting of a coil spring carried by the cover and engaging against the top of the soap cake.

5. A dispensing device of the character described comprising a casing having a movable top and having its bottom formed with a discharge opening, an inner casing slideable within said main casing and having a 70 discharge spout extending through said discharge opening, a pair of grinding rollers journaled in the inner casing, said inner casing being designed to hold a cake of soap placed upon said rollers, and an operative 75 connection between said inner casing and the rollers whereby to rotate the latter when said inner casing is slid upwardly, said connection consisting of gears on said rollers, and a toothed element mounted within the 80 outer casing and meshing with the gears.

In testimony whereof I affix my signature.

JOHN LOUIS GAEBEL.
